Patented Aug. 31, 1920.

2 SHEETS—SHEET 2.

UNITED STATES PATENT OFFICE.

DORÉ W. GRAZIER, OF JOHNSTOWN, PENNSYLVANIA.

AUTOMOBILE-SIGNAL.

1,351,513.

Specification of Letters Patent. Patented Aug. 31, 1920.

Application filed February 24, 1920. Serial No. 360,738.

To all whom it may concern:

Be it known that I, DORÉ W. GRAZIER, a citizen of the United States, residing at Johnstown, in the county of Cambria and State of Pennsylvania, have invented a new and useful Automobile-Signal, of which the following is a specification.

This invention has reference to signaling devices, and more particularly to mechanical signals employed on motor vehicles, for indicating to persons at the rear of the machine the intended direction of travel thereof.

The primary object of the invention is to provide a device of this character which will be purely automatic in one of its movements, one which will readily respond to the operating means, and one which will indicate in daylight as efficiently as in the dark.

A further object of the invention is to provide a signaling body including a casing and a movable signaling member within the casing, the bearings for supporting the movable signaling member forming lamp sockets to receive lamps for illuminating the signs.

With the foregoing and other objects in view which will appear as the description proceeds, the invention resides in the combination and arrangement of parts and in the details of the construction hereinafter described and claimed, it being understood that changes in the precise embodiment of the invention herein disclosed, may be made within the scope of what is claimed, without departing from the spirit of the invention.

Referring to the drawings:

Figure 1 illustrates a side elevational view of a motor vehicle supplied with a signaling device constructed in accordance with the present invention.

Fig. 2 illustrates a longitudinal sectional view taken on line 2—2 of Fig. 1.

Fig. 3 illustrates a transverse sectional view taken on line 3—3 of Fig. 2.

Fig. 4 illustrates a sectional view taken on line 4—4 of Fig. 2.

Fig. 5 illustrates a plan view of the operating lever, and

Fig. 6 illustrates a sectional view taken on line 6—6 of Fig. 5.

Referring to the drawings in detail, the reference character 5 designates the casing of the signaling device, which is shown as supported by the bracket 6 and has connection with one of the rear mud guards of

the automobile, to which the device is applied.

This casing 5 is preferably circular in cross section as indicated by Fig. 3 of the drawings, and is provided with a flared portion 7 having inturned flanges 8 to provide supporting means for the lens 9 through which the rotating signal member may be observed.

End sections 10 form a part of the casing 5, and are apertured substantially centrally thereof, the walls of the apertures being preferably threaded to receive the threaded portions of the sockets 11 which are shown as positioned in the openings, there being a threaded washer 12, secured to the inner wall of each end section 10, embracing portions of the sockets 11 and adapted to coöperate with the annular flange 13 of the respective socket members for clamping the socket 75 members to the end sections.

The brackets 6 are disposed at opposite ends of the casing 5 and have forked extremities, the upper forked extremity of each bracket being provided with openings 80 to accommodate securing means which means is adapted to pass through predetermined openings formed in the end sections 10, and since there are a plurality of these openings provided, it will be obvious that 85 the connection between the casing and the brackets may be changed to support the casing at various angles, at the will of the operator. The bolts 14 are employed for securing the bracket 6 to the end sections 10 90 in a manner to prevent movement of the casing with relation to the brackets.

The socket members 11 are tubular, and relatively long so that portions thereof extend an appreciable distance within the casing 5, to provide bearings for the inner signaling member 15 which is box-like in formation, the side walls thereof being formed of a continuous strip of metal bent at predetermined points to provide side 100 members, and as shown these side members are cut out to form indicating characters, which in the drawings are shown as words indicating direction of travel.

A stencil 16' forms one of the side walls 105 of the signaling member, which stencil is provided with a cut out portion backed by a red glass to provide a tail light but it is to be understood that this stencil may be constructed in any suitable manner, to meet va- 110

rious requirements of use. The stencil 16' together with its backing 15' are inserted through the opening 22' formed at one end of the inner signaling member 15, so that these plates and backings may be readily removed and replaced in the event that it is found desirable to supplement another form of stencil or backing.

Relatively square metallic end sections 16 form a part of the inner signaling member and each of these end sections is provided with an offset portion 17 to provide grooves to receive the ends of the metallic member forming the side walls of the inner signaling member 15, together with the ends of the plates 15' formed of suitable translucent material.

Secured to each of the end sections 16 are the drums 18 and 19, the drum 18 being provided with a groove 20 adapted to receive the flexible means employed for operating the inner signaling member, the flexible operating means being shown at 21 and has one of its ends secured to the drum 18 by means of the screw 22, a portion of the flexible member being wound on the drum 18 so that movement of the flexible member 21 in one direction causes a rotary movement to be imparted to the inner signaling member 15.

The drum 19, disposed at the opposite end of the signaling member 15 provides a support for one end of the coiled spring 23, the opposite end of said coiled spring having connection with the inner walls of the casing as at 24, so that when the flexible member 21 is moved, in a predetermined direction, the coiled spring 23 is wound about the drum 19 to increase the tension thereof with the result that when the flexible member 21 is released, the inner signaling member 15 is automatically returned to its normal position.

Both of these drums 18 and 19 are supported on the socket members 11, as clearly illustrated by Fig. 2 of the drawings, and are free to revolve thereon, thus presenting a structure to readily respond to the flexible operating member 21 to the end that the signaling member 15 may be readily and easily operated.

In order that the end sections 16 may be supported in proper spaced relation to each other to eliminate any possibility of the side walls of the inner signaling member 15 rattling, or working loose, relatively long connecting rods 25 are provided, which rods have the usual heads 26 formed on one of the respective ends thereof, the opposite ends of said rods being threaded to accommodate the nuts 27.

Electric lamps 28 are positioned in the lamp sockets and are supplied with electric current through the plugs 29 and circuit 30 which extends through a suitable opening

provided in the body of the automobile, where the same will have connection with an electric current supply, not shown, in the usual and well known manner.

A tubular member 31 has connection with the rear of the casing 5 and extends forward, terminating at a point adjacent the operating lever 32, which as shown, is supported on the dash or other convenient place of an automobile to which the signal is applied, so that the same would be disposed in a position to be readily manipulated by the operator of the car.

The tubular member 31 houses the flexible member 21, which flexible member 21 has connection with the operating lever 32 which also has connection with the drum 33 so that when the lever 33 is operated, the flexible member 21 may be coiled or wound around the drum to cause the operation of the inner signaling member 15.

The location of the inner signaling member 15 with relation to its casing 5, is such that one of the side walls of the signaling members 15 is in constant register with the lens 9, or in a position so that the indicating characters thereon may be readily observed through the lens 9.

In the operation of the device, assuming that an automobile equipped with the signaling device is to take a direction to the left of the path of travel of the machine, the operating lever 32 is wound on the drum 33, the drum being of a diameter equal to the diameter of the drum 8 causes the side wall 100 of the inner signaling member 15 which carries the inscription Right to be moved to a position in registry with the lens 9. It follows that on movement of the lever to a position opposite to that shown in Fig. 5, the word Stop is brought to an indicating position, and when the lever 32 is moved farther to the left, the inscription Left is moved to an indicating position.

From the foregoing it is obvious that persons at the rear of a machine equipped with an indicating device constructed in accordance with the present invention, may readily determine the course which the machine is to take.

It will of course be understood that for various movements of the car, various movements of the inner signaling member 15 are accomplished for indicating.

Having thus described the invention, what I claim as new is:—

1. In a signaling device, a casing, an inner signaling member supported within the casing, said inner signaling member including side walls, said side walls having cut out portions indicating direction, end sections having offset portions providing seats for the side walls, connecting rods having connection with the end sections for securing the end sections in proper spaced rela- 130

tion, lamp sockets carried by the casing, said inner signaling member adapted to rotate on said lamp sockets, means for moving the inner signaling member in one direction, 5 and means for returning the inner signaling member to its normal position.

2. In a signaling device, a casing, said casing including end sections, said end sections having central openings a lamp socket 10 having a threaded portion adapted to be positioned within each of the openings, said lamp sockets extending into the casing, each of said lamp sockets having a flange adapted to engage the end sections, a threaded ring 15 operating on the threaded portion of each of the lamp sockets and coöperating with the flanges for securing the lamp sockets to the casing, an inner signaling member supported on the lamp sockets, flexible means 20 for moving the signaling member in one di-

rection, and means for returning the signaling member to its normal position.

3. In a signaling device, a casing, an inner signaling member supported within the casing, said inner signaling member comprising, end sections, each of said end sections having offset portions to provide grooves, metallic members forming the side walls of the inner signaling member, and positioned within the grooves, and one of 25 said offset members being provided with an opening to permit one of said side members to be removed therefrom.

In testimony that I claim the foregoing as my own, I have hereto affixed my signature in the presence of two witnesses.

DORÉ W. GRAZIER.
